[57] CLAIM

The ornamental design for a telephone handset, as shown and described.

DESCRIPTION

FIG. 1 is a front, bottom and side perspective view of a telephone handset, showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a front elevational view of a second embodiment of our new design;

FIG. 9 is a right side elevational view thereof;

FIG. 10 is a left side elevational view thereof;

FIG. 11 is a top plan view thereof;

FIG. 12 is a bottom plan view thereof;

FIG. 13 is rear elevational view thereof;

FIG. 14 is a front, bottom and side perspective view of a third embodiment of our new design;

FIG. 15 is a front elevational view thereof;

FIG. 16 is a right side elevational view thereof;

FIG. 17 is a left side elevational view thereof;

FIG. 18 is a top plan view thereof;

FIG. 19 is a bottom plan view thereof;

FIG. 20 is a rear elevational view thereof;

FIG. 21 is a front, bottom and side perspective view of a fourth embodiment of our new design;

FIG. 22 is a front elevational view thereof;

FIG. 23 is a right side elevational view thereof;

FIG. 24 is a left side elevational view thereof;

FIG. 25 is a top plan view thereof;

FIG. 26 is a bottom plan view thereof;

FIG. 27 is a rear elevational view thereof;

FIG. 28 is a front, bottom and side perspective view of a fifth embodiment of our new design;

FIG. 29 is a front elevational view thereof;

FIG. 30 is a right side elevational view thereof;

FIG. 31 is a left side elevational view thereof;

FIG. 32 is a top plan view thereof;

FIG. 33 is a bottom plan view thereof; and,

FIG. 34 is a rear elevational view thereof.
